UNITED STATES PATENT OFFICE

ARTHUR M. WILHELM, OF RANDOLPH, NEW YORK

AVIATION MARKER

Application filed February 13, 1931. Serial No. 515,605.

This invention relates to certain new and useful improvements in markers for aviation.

During winter flying the markers which are provided along the airways across country are easily obscured by the slightest snow, or other matter, such as the leaves from the trees, and consequently the aviator derives no benefit from the concealed marker. This is equally true with respect to markers at airports, and advertisements or other indicia specially designed for aviators. Further during night driving these signs and markers may be illuminated but the manner of illumination, and the construction of the signs or markers, are such that they are not distinctly and clearly discernible to the aviator.

The object of the present invention is to provide an all-weather marker which will be visible and readily discernible from the air; and further one which can not be easily obscured by snow.

The invention further contemplates the provision of a marker which may readily be seen from the air regardless of the angle of approach, and one which may be illuminated so as to clearly and distinctly stand out as a reliable guide for the aviator during night travel.

For a clear understanding of the invention, reference is made to the following description in conjunction with the attached drawings wherein:

Fig. 1 is a top plan view of a marker embodying the present invention.

Fig. 2 is a transverse sectional view therethrough about on line 2-2 of Fig. 1.

Fig. 3 is a fragmentary perspective view of the marker.

Fig. 4 is a view similar to Fig. 1 but depicting a slightly modified illuminating arrangement.

Fig. 5 is a fragmentary sectional view of the modified marker of Fig. 4.

In proceeding in accordance with the present invention the marker may be in the form of a direction indicating element, such as the arrow indicated in Fig. 4, or it may be in the form of a sign or advertisement composed of individual letters, such as is indicated in Fig. 1. By the use of letters the name of the

airport may be displayed as a guide to the aviator. So that the term "marker" is herein used broadly to include a sign or advertisement or other designation to be conveyed to the aviator, and in fact the inventive concept herein expressed may be utilized for other traffic designations such as road markings, wherein the present invention might be utilized.

In accordance with this invention I provide a sign having a top or upper face formed of an open mesh work to provide for the ready passage of snow, or other matter, therethrough in a manner to clear the marker and without impairing the full and complete functioning of the device. To this end each mesh opening is made sufficiently large to enable the free passage of snow entirely through without clogging tendency.

The marker is herein depicted as comprising marginal side walls 1 which define a frame that delineates the general design or outline of the marker. The space between the marginal walls 1 is filled by an open mesh fabrication the openings of which may be of any desired geometric design although the present disclosure illustrates the openings as being rectangular in design. The open mesh work is formed by a row of parallel plates 2 intersected by a transverse row of plates 3, which plates are of a sufficient depth to expose considerable wall surface when viewed from an airplane. In practice it is preferred to space the filler plates in the row eighteen inches or two feet apart so as to provide large open spaces 4 throughout the top surface area of the marker, or substantially throughout such area. The large individual openings 4 are provided of such extent as to avoid the possibility of snow and ice clogging the same with the ultimate complete coverage and concealment of the marker. These large openings will present a mesh or foraminous appearance from the air which will be further accentuated by the shadows cast on and by the intersecting walls. These intersecting walls have thin or very narrow top edges to avoid little accumulation of snow on the top edges. Es-

pecially with a wind blowing any accumulation of matter will be negligible.

An aviator usually looks down at not a greater angle than 45° and by making the plates 2 and 3 of a depth say one half again that of the cross sectional dimension of the opening 4, sufficient wall space will be presented to view so that the aviator will in effect obtain the benefit of a solid wall area 10 of the marker for normal cruising and flying purposes. The side walls of the openings may be polished or painted in a bright color, such as orange, which will serve to set off the marker when the sun is shining thereon, 15 or when the same is illuminated for night usage. The openings 4 have unobstructed discharge from the bottom face of the marker and in order to provide for free escape of snow and other matter from beneath the 20 marker after having passed therethrough, and against piling up ultimately to clog the openings, the marker is elevated a substantial distance above the ground as by means of supports 5. These supports may be anchored in a concrete base 6 if desired.

For night use the marker may be illuminated by different light sources 7 dispersed at proper intervals to have their light rays reflected by the vertical walls 2 and 3, and 30 where the marker is of considerable breadth or area, additional lighting may be provided by a suitable arrangement of flood lights indicated generally at 8. As an alternative the illumination may be provided by neon tubes 35 9 by which the marker may be well delineated as well as having its light reflecting walls 2 and 3 illuminated.

The marginal walls 1 may be provided along their lower edges with depending skirt portions 10 which extend inwardly beneath the marker body at a downward inclination to serve as a means for deflecting the wind downwardly, thereby to assist in maintaining the space beneath the marker body clear 45 and free from accumulated matter.

This marker may be used not only at airports but also along airways to direct aviators, or it may be mounted on the tops of buildings and other surfaces from which the 50 marker may be read from above. The reference in the claims to an aviation marker is therefore used in this broad sense, since the invention can be used equally well for signs and advertisements having a top surface through which the vertical tubes open 55 for the ready passage of snow and other matter. These tubes preferably have straight vertical walls but slight variations therefrom to increase the wall surface, when viewed from a point more nearly to the perpendicular, are comprehended herein.

What is claimed is:

1. A marker for aviation, visible from the 60 air, comprising a body having a definite form with a top or upper surface area having

large openings presenting from the air an open mesh appearance, the mesh openings being defined by walls of greater depth than the cross sectional dimensions of the individual openings to present a substantially 70 solid wall appearance when viewed from an angle to the ground perpendicular, the said openings passing entirely through the top and bottom faces of the marker whereby falling matter may pass through and free of the 75 marker.

2. A marker for aviation, visible from the air, comprising a body having a definite form with a top or upper surface area of open mesh, the mesh openings being defined by walls extending downwardly through the body of the marker and defining mesh openings in the top and bottom faces of the marker, and a source of night illumination arranged beneath the open mesh bottom face 80 for illuminating the walls for view through the open mesh top face from the air.

3. A marker comprising a body having a definite form with a top or upper surface area formed of open mesh, the mesh openings being defined by walls forming substantially perpendicular light reflecting surfaces for viewing from above, and a source of illumination arranged for illuminating the light reflecting walls, and means supporting the body for the free escape of matter falling through the mesh openings, said body having an open bottom for such escape.

4. A marker for aviation, visible from the air, comprising a body having marginal walls defining a definite form with a top or upper surface area formed of open mesh having mesh openings each of a cross sectional dimension to freely pass wind-blown matter therethrough, said body having an open bottom for the escape of such matter, and a source of illumination carried by the marginal wall of the body and delineating the outline thereof.

5. A marker for aviation, visible to aviators while flying, comprising a body having a definite form and composed of a plurality of intersecting plates substantially perpendicular to the ground and forming an open mesh top face for the marker, the openings in the top face extending through the body and opening through the bottom face of the body, and means supporting the body with the bottom face spaced from off the ground whereby any matter passing through the openings of the body will have free escape from beneath the marker.

6. An aviation marker of definite form and comprising spaced side walls and a plurality of intersecting filler walls arranged between the side walls, said filler walls being arranged on edge and intersecting each other to form a foraminous upper surface area for the marker between the side walls thereof, the openings of the foraminous upper surface

opening through the bottom portion of said marker, and said walls being of greater depth than the cross dimension of the openings.

7. An aviation marker comprising a body having a definite form and an upper surface area perforated for the passage of wind-blown matter therethrough for discharge through the bottom portion of the body, means supporting the body above the ground, and means arranged adjacent the lower edge of the body, above the ground, for deflecting the wind toward the ground to clear the space beneath the body from accumulated matter.

DISCLAIMER

1,847,739.—*Arthur M. Wilhelm*, Randolph, N. Y. AVIATION MARKER. Patent dated March 1, 1932. Disclaimer filed February 3, 1933, by the patentee.

I disclaim the subject matter of claims 1 and 2 of my Patent No. 1,847,739, except as they apply to an aviation marker having an external information-imparting shape.
